UNITED STATES PATENT OFFICE.

HARRY J. WELCH, OF GRAFTON, OHIO.

BROODER.

1,410,632.

Specification of Letters Patent. Patented Mar. 28, 1922.

Application filed June 18, 1919, Serial No. 304,995. Renewed February 14, 1922. Serial No. 536,545.

To all whom it may concern:

Be it known that I, HARRY J. WELCH, a citizen of the United States, and a resident of Grafton, in the county of Lorain and 5 State of Ohio, have invented certain new and useful Improvements in Brooders, of which the following is a specification.

My invention relates to brooders, and has reference more particularly to portable 10 brooders in which no hovers are used, a proper circulation of air is maintained and the body portions of the chicks receive the necessary amount of heat for their maintenance.

15 An object of my invention is to provide a brooder in which the air is properly heated prior to its entrance in to the brooder chamber through a reticulated floor, which in itself is self cleaning.

20 Another object is to provide a brooder which can be used equally well indoors and outdoors.

Another object is to provide a brooder which is adapted to be used outdoors, and 25 the circulation of air therethrough properly regulated, and also having provisions against draft and abnormal winds.

Another object is to provide a brooder that is self cleaning and one having means 30 to conserve and save the excrement incident to this character of devices, for use as a by product.

Another object is to provide a brooder, which saves the excrement and conditions 35 the same, and at the same time remove the danger of foul gases arising therefrom.

With these and other objects in view, my 40 invention consists mainly in providing a brooding chamber with a reticulated floor which is self cleaning and provides free entrance and circulation of warm air therethrough.

My invention consists further in certain 45 novel features of construction, arrangement and combination of various parts and elements, as will be hereinafter described and pointed out in the claims, reference being had to the accompanying drawing forming part hereof, and in which:

50 Figure 1 is a perspective view constructed according to my invention.

Figure 2 is a vertical longitudinal section of same,

Figure 3 is a vertical transverse section.

Figure 4 is a fragmentary view showing 55 a gas pipe and burner means.

In carrying out the invention as embodied in the form selected, which is mainly intended for out door use, I provide an open frame composed of the uprights A mounted 60 on the runners B which are turned upwardly at each end and connected by cross beams B', forming practically a sled structure by which the device as a whole can be pulled or pushed from place to place. 65

To the upper ends of the uprights A, is secured an inverted traylike structure C having a large central opening C', which is covered by screen D of wire cloth, of varying degrees of mesh; that is, about one 70 third of the screen has a $\frac{1}{4}$ inch mesh, the next third, $\frac{1}{2}$ inch mesh and the remaining third is composed of $\frac{1}{8}$ inch mesh.

The walls C² of the part C curve outwardly and downwardly as shown, and in 75 one end wall openings C³ and C⁴ are made to receive a gas pipe E and a compressed air pipe F, the gas pipe running beneath the screen D within heat distributing tubes D' which are mounted beneath said screen 80 in rows or any other suitable manner, and also beneath the deflecting and discharge plate G which will be hereinafter more specifically described. The gas pipes are provided with slits e which are made in said 85 pipe at intervals and in rows, the slits of one row overlapping those of the next row.

The screen D constituting the floor of the brooding chamber and as before stated, is composed of varying mesh wire, and these 90 portions are separated from each other by transverse partitions D², which extend between the side walls D³ dividing the brooder chamber into three compartments D⁴, D⁵, and D⁶ into which chicks of different ages 95 are to be placed; thus the youngest and smallest chicks are placed in compartments D⁴ which has the smallest mesh floor; the next larger and older in compartment D⁵, and the largest and oldest chicks in D⁶. 100 The chamber is provided with the end walls D⁷ in each of which is an opening D⁸ guarded by a wire mesh door D⁹ hinged at its lower end so that it may open outwardly and downwardly. Above said doors D⁹ are thin 105 imperforate shutters D¹⁰ hinged at their upper ends to end walls D⁷ and D⁸ and held normally away from the same at an angle

by the coiled springs D¹¹; these shutters are so hinged and are of such length that a stiff breeze against them will force them down and prevent the wind blowing 5 through the reticulated doors D⁹.

The transverse partitions D² are made in two sections, the lower section D¹³ being hinged to the upper portions to swing and permit the chicks to go from one compartment to another; the upper portions of the partitions are also provided with openings D¹⁴ to receive the water supply tank D¹⁵ which supplies water to the water trough or gutter D¹⁶ which extends longitudinally 10 through the center of the brood chamber and in each compartment, the water being supplied to the trough by the tubes D¹⁷ and extending from tube to tube in the longitudinal center of each compartment is a 15 vertical longitudinal plate D¹⁸ which extends down into the trough which will prevent the chicks from getting into the water trough, for if they attempt to jump upon the edges of the trough, their heads come 20 in contact with this longitudinal partition or plate D¹⁸ and they are forced back thereby. The tank D¹⁵ has an opening in the top D¹⁹, controlled by a cap D²⁰ and as the lower ends of the tubes D¹⁷ extend down 25 into the trough D¹⁶ the trough will maintain a constant level of water as the water supply device is of the barometric type.

To render the device self-feeding, I provide along the sides of the brood chamber 30 within the same the feed troughs H open at their top and rear, the rear abutting the long openings H' in the lower end of the side walls D³ and communicating with these 35 openings are the feed hoppers built on the outside of the walls, said hoppers comprising an inclined outer wall H², the floor H³ and hinged cover H⁴ which overhangs the top opening of the feed hopper and prevents 40 entrance of rain, etc. This top door permits of filling the feed hopper and as the hopper tapers inwardly and downwardly, the feed in the hopper will automatically 45 flow into the trough in the brood chamber by the action of gravity, as long as any feed 50 remains in the hopper.

Extending upwardly from the brood chamber, which is open at the top, at each end and at the corners thereof, are the masts or poles I which may be provided with a 55 series of peg openings in which may be inserted pegs to support a roof structure J which is of the gable type, or the upper ends of the masts I may be connected by cross bars I' having at their center a pulley 60 block I² on which is carried a cord I³ secured at one end to the ridge of the roof and having a counterweight I⁴ at its free end, by which the roof may be adjusted and maintained in adjusted position. Windows J⁵ are also provided in the roof. 65

The roof structure comprises the ridge pole J' and the side members secured to the said ridge pole, said side members being composed of three layers, a lower layer J² of wire and intermediate layer J³ of cloth, 70 and an upper or outer layer of wire J⁴, this outer layer being made of wire for the purpose of preventing wind from tearing the cloth layer, as the meshes of the outer wire layer will break up the direct current of 75 the wind and materially lessen its force.

As hereinbefore stated, beneath the air chamber C which extends below the reticulated floor of the brooder chamber, a deflecting and discharging plate G is placed. This 80 plate which is of metal, is secured at its upper end to the inside of the air feeding chamber C as at G' adjacent the upper ends of the uprights A and extends diagonally downward at about any desirable angle to 85 the opposite side of the open frame formed by the said uprights A and their supporting runners.

As will be noted the pipes of the heating system extend beneath this inclined plate G 90 as well as through the air chamber C. Now it is a well known fact that the excrement from chickens contains considerable ammonia, and as it is dropped in a moist condition, a foul and poisonous vapor arises 95 from the excrement while in a moist or wet condition. In my device the excrement as it falls on the inclined plates, G, is immediately dried by the heat thereof and is deprived of the poisonous vapor or gas and 100 rolls downwardly and is discharged into a receptacle placed appropriately for that purpose, to be used as a by product which is of well known value.

As the floor D of the brooding chamber 105 is entirely unobstructed, being of wire mesh, air passes freely through it and all around the chicks, and the air before entering is heated by the pipes D' to the proper temperature best adapted for rearing young 110 chickens.

The reason for making sections or different areas of the floor of the brood chamber of wire screen of varying mesh is that the size of the fecal discharges of chicks of different ages and sizes differ, and that a uniform mesh may not take care of all ages; thus the discharge of youngest chicks is small 115 enough to freely pass through the $\frac{1}{4}$ inch mesh, but for the discharge of the slightly older and larger chicks, this is not true, as the discharge is larger and will not pass through the $\frac{1}{4}$ inch mesh, and hence a slightly larger mesh or $\frac{1}{2}$ inch is necessary, and so on as the number of compartments and groups 120 of chicks are handled.

It has been found that by using a perfectly free and unobstructed reticulated floor for the brooding chamber, that the wire mesh is self cleaning and hence the brooding chamber 125

ber cannot become fouled by accumulations which are known to breed the diseases that take such a large toll of life in chicks, especially chicks that are hatched by incubators 5 and then placed in brooders.

While usually the natural draft through the reticulated floor is sufficient to provide perfect circulation of air, I may sometimes find it desirable to employ a forced draft 10 and for this purpose, I employ the air pipe F running into the air chamber C in any suitable manner and connected up with any suitable blower vacuum pump, or air forcing means.

15 The perforated gates D^o at each end of the brood chamber serve double purposes, to wit: they act as an air outlet and inlet and they may be swung down on bent wall C' of the air chamber C and form a preliminary runway to the usual inclined runway, the hinged 20 lower sections of the transverse partitions permitting the passage of the chicks through the various compartments.

By raising and lowering the roof member, 25 the circulation of air through the device can be regulated and controlled according to the prevailing weather conditions when the device is used outdoors. When the device is to be used indoors, the roof or superstructure 30 may be removed entirely as there will be no need in such use to protect the upper open part of the brood chamber from the elements.

While I have shown gas burning devices employed as the heating medium, because 35 natural or producer gas is more convenient in many localities, yet the apparatus will function just as effectively with any other heating systems, such as hot water, gas, electric, etc., and the structural arrangements of 40 the parts may be varied to suit various conditions, the main essential being that a perfectly free and unobstructed lower air inlet to the brooder chamber be provided and be of such a character as to prevent the fouling 45 of such chamber.

At M I have shown a lamp which is to be applied to the brood chamber, it being important that some form of permanent illumination be used in rearing young chickens, 50 as when under ordinary circumstances, darkness comes on the natural tendency of young chickens is to huddle up and thus cause overcrowding and consequent injury.

With illuminating means active at all 55 times within the brood chamber, this defect is wholly overcome. I may use any suitable illuminating means such as gas light, electric lights, etc.

In the installation of the heating means 60 for heating the air before its passage through the floor, it is important that the pipes or elements for disseminating the heat should be placed some distance apart, preferably near the sides of the brood chamber, so that 65 there will be varying temperature from the

center to the sides, the lower temperature being at the center and of course increasing to the sides. The object of this specific arrangement is to prevent overheating the chicks and providing means for seeking the 70 most beneficially heated area.

I claim:

1. A chicken brooder comprising a chamber having side and end walls and open at its top and bottom, a reticulated wall covering the entire bottom, an air chamber flaring outwardly and downwardly from said reticulated bottom, heating elements located within the flaring, and supporting means upon which said air chamber and casing are 75 mounted.

2. A chicken brooder, comprising a casing having side and end walls and open at its top and bottom, an adjustable and removable covering therefor, a reticulated wall 80 covering the entire opening at the bottom, an expanded air chamber projecting below said bottom wall, and air heating means carried within the flaring of said expanded chamber. 85

3. A chicken brooder comprising a casing having side and end walls, and a reticulated bottom wall, an air chamber projecting below said reticulated bottom, means for heating the air in said chamber, and an inclined 90 drying and discharging plate mounted within said air chamber, and means for heating said plate. 95

4. A chicken brooder comprising a casing having side and end walls, a series of transverse partitions between the side walls dividing the casing into chick chambers, an open top, and a reticulated bottom wall beneath said chambers, the reticulations varying in diameter in predetermined areas defined by said partitions and the side walls, whereby each area is limited to chicks of a certain size. 100

5. A chicken brooder comprising a casing having side and end walls, an open top, 110 transverse partitions composed of an upper section and a lower section hinged thereto and dividing said casing into compartments, a reticulate lower wall for each compartment, the reticulations in the bottom walls 115 increasing successively in size from one end of the casing to the other end, the size of the reticulations in each compartment being different.

6. A chicken brooder comprising an open 120 supporting frame, a downwardly and outwardly flared air chamber mounted thereon, heating means positioned within the flaring, said chamber having a reticulated upper wall, a brooding chamber supported on said 125 air chamber, said reticulated upper wall constituting the floor of the brooding chamber, said brooding chamber including side and end walls and open at the top, said side walls having passages therethrough, the end 130

walls having reticulated inlet and outlet means, spring means for automatically controlling said inlet and outlet means, a superposed roof member, said roof member having over hanging eaves with respect to the brooding chamber, and vertically adjustable, and counterbalanced.

7. A chicken brooder comprising a casing having side and end walls and open at its

top and bottom, a removable cover therefor, 10 a reticulated wall covering the entire opening at the bottom, a downwardly flared air chamber projecting below said bottom wall, and means adjacent the side and end walls of the casing for heating said air chamber, 15 whereby the greatest heat will be received at the sides and the ends of the casing.

HARRY J. WELCH.
